LADDER BRACKET

Harold O. Weisgraber, Norwich, Conn.

Application August 18, 1933, Serial No. 685,718

4 Claims. (Cl. 304—34)

This invention relates to a ladder bracket for mounting a platform on a pair of spaced ladders to form a scaffolding for painting or doing other work on the side of a building.

Various structures have been previously devised for this purpose and have consisted generally of a horizontal arm having a means at one end enabling it to be hooked onto one rung of the ladder, and of an inclined arm secured at its lower end to the free end of the horizontal arm and at its upper end to the one of the higher rungs of the ladder. The platform is then supported upon the horizontal arm. However, it is desirable in many cases to provide a ladder bracket which may be mounted either on the upper or the lower side of a ladder. Previously devised structures have been designed for use either on the upper side only or on the lower side only, and when placed on the opposite side for which they were intended they have been found not to function efficiently.

When a device of this character is mounted on the lower side of a ladder, a relatively short inclined arm is necessary, and this arm will extend upwardly in a relatively upright position, whereas when the device is mounted on the upper side of the ladder a much longer arm is required, and assuming that both arms are straight, the sharp inclination of the inclined arm with respect to the horizontal arm will serve to greatly limit the space provided for reception of the platform on the horizontal arm and between the two arms. The general result as will be appreciated will be similar to the closing of a pair of shears upon the platform.

It is therefore the object of this invention to provide a device of this type which may be mounted on the lower side of a ladder, and which may be shifted to the upper side of the ladder and mounted thereon in such a manner as not to unduly limit the space provided for the reception of the platform. It is an object also to provide an attachment which may be made a part of the ladder bracket in mounting it on the upper side of the ladder, said attachment being adapted to form an extension for the inclined member to provide the additional length required, and at the same time to so position the inclined member that it will not interfere with the proper positioning of the platform on the horizontal member.

With the above and other objects in view this invention consists of certain parts and combinations one embodiment of which is set forth in the following description and the accompanying drawing.

In the drawing:—

Figure 1 is a view partly in section illustrating an embodiment of the invention for suspension on the underside of a ladder.

Figure 2 is a view similar to Figure 1 illustrating another embodiment of the invention and of the type for suspension on the upper side of a ladder.

Figure 3 is a sectional view taken along the line 3—3 of Figure 1.

Figure 4 is a perspective view illustrating the extension member forming an element of that embodiment of the invention shown in Figure 2.

Figure 5 is a perspective view illustrating the form of inclined arm or hanger element employed in both embodiments of the invention.

Figure 6 is a view illustrating the form of horizontal arm or supporting element employed in both embodiments of the invention for supporting the platform or scaffold.

Figure 7 is a plan view illustrating a device for extending between the ladder and the structure against which it is supported for preventing the ladder from slipping while the ladder bracket of this invention is in use thereon.

Referring first to Figure 1 of the drawing there is shown a ladder having side members 1 and rungs 2, the side members 1 being disposed at an inclination with respect to the vertical in the manner customary when a ladder is placed against a building or other support.

The embodiment of the invention as shown in Figure 1 is for the purpose of supporting a scaffold 3 from the underside of ladder 1, and such embodiment comprises a supporting element or horizontal arm and a hanger element or inclined arm. The embodiment of the invention as shown in Figure 2 is for the purpose of supporting the scaffold 3 from the upper side of the ladder and such embodiment comprises a supporting element or horizontal arm, a hanger element or inclined arm and an extension element or member. In both embodiments of the invention the supporting elements are of like construction, and the hanger elements also are of like construction. Like reference characters are employed for the supporting elements and for the hanger elements of both embodiments of the invention.

The supporting element or horizontal arm of each embodiment is generally indicated at 4 and comprises a head and a stem. The latter being integral at one end with one side of the head centrally of the latter. The head includes a solid oblong central part 5 having each of its ends provided with a lateral extension 6. Oppositely disposed elbow fittings 7 are mounted on and project from the extensions 6. Each elbow 7 includes

a horizontal and a vertical portion. The latter being extended upwardly from the outer end of the horizontal portion. Mounted in the vertical portions of the elbows 7 are upstanding hooks 8 and these latter are adapted to engage one of the lower rungs of the ladder 1. The hooks 8 may be anchored to said vertical portions in any suitable manner and shown by way of example as being anchored by the bushings 9. The stem of element 4 is formed of a solid stretch 4' and a hollow stretch 10. The stretch 4' is of greater length than stretch 10, merges at one end into one side of central part 5 and at its other end into one end of stretch 10. The height of stretch 4' is less than 15 and has its top face positioned below the tops of part 5 and stretch 10 whereby there will be provided at the ends of stretch 4' abutments 10' to arrest the shifting of the platform or scaffold 3 upon the supporting element 4. The stretch 10 is in the form of an oval-shaped loop to provide a vertical opening 11 in the stem of element 4. The sides of the loop formed by stretch 10 are formed with transversely disposed aligning openings 12. The hanger element or inclined arm of each 20 embodiment of the invention is generally indicated at 13 and comprises a shank terminating at one end into a hook 14 adapted to engage with an upper rung of the ladder 1. The shank is formed of a pair of stretches 13', 15. The stretch 13' merges at one end into the hook 14 and at its other end merges into the inner end of stretch 15. The side faces of stretch 13' are disposed at right angles to the side faces of the stretch 15. The latter is of less thickness than that of stretch 13' 25 and is formed with a row of spaced openings 16 extending lengthwise thereof.

Each supporting element or horizontal arm 4 carries a chain 18 to which is connected a securing pin 17 for a purpose to be referred to.

When the embodiment of the invention as shown in Figure 1 is employed for supporting or suspending the scaffold or platform 3 on the under side of the ladder, the hooks 8 of the supporting element are detachably connected to a lower rung 40 of the ladder and such element is to extend rearwardly with respect to the ladder. The hanger element is to have its hook positioned in engagement with an upper rung of the ladder. The looped stretch of the supporting element is then positioned to overlap the stretch 15 of the hanger element in a manner whereby the openings 12 will align with an opening 16. The securing pin 17 is then extended through the aligning openings 12, 16, whereby the parts will appear as shown in Figure 1 with the platform or scaffold 3 mounted in stretch 4' between the abutments 10'.

The extension element or member generally indicated at 19 forms a part of the embodiment of the invention as illustrated by Figure 2 and it 45 comprises a curved solid inner stretch 19' merging into oppositely inclined upper and lower stretches 19'', 24 respectively. The stretch 19'' is bifurcated and the arms 20 formed by the furcation are provided with aligning openings 21. The stretch 24 is of greater length than stretch 19'' and is 50 formed with a row of spaced openings 25 extending lengthwise thereof.

When the embodiment of the invention as 55 shown in Figure 2 is employed for supporting or suspending the scaffold or platform 3 from the upper or front side of the ladder, the hooks 8 of the supporting element are detachably connected to a lower rung of the ladder and said element is to extend forwardly from the ladder. The hanger element is to have its hook positioned in engage-

ment with an upper rung of the ladder. The bifurcated stretch 19'' of element 19 is then positioned upon the stretch 15 of element 13 in a manner whereby one or more of the openings 21 will align with one or more of the openings 16. The stretch 19'' is then rigidly but removably secured to the stretch 15 by bolts 22 having wing nuts 23. The stretch 24 of element 19 is then extended into the looped end of element 4 in a manner to align one of the openings 25 in stretch 24 with the openings 12 and the securing pin 17 extended through the aligning openings 12 and 25 whereby the parts will appear as shown in Figure 2, and the platform or scaffold supported by the stretch 4' between the abutments 10'.

With reference to Figure 2, it will be seen that when the supporting element or horizontal arm, and the hanger element or inclined arm are placed on the upper side of the ladder, the hanger element is of insufficient length to enable it to be secured to the looped outer end of the supporting element, and even if extended so that it will have sufficient length, it would be inclined with respect to the supporting element at such an angle that it would interfere with the platform or scaffold 3. This difficulty is overcome by the curved extension element or member 19 as arranged in the manner shown in Figure 2, and when so arranged the upper portion of the extension element is maintained entirely clear of the platform or scaffold 3.

Whether the device is mounted on the under side or on the upper side of the ladder, it will be seen that the spaced hooks 8 will serve to positively prevent the horizontal arm 4 from tilting, and that the fact that these hooks extend upwardly will enable the weight exerted upon them to be exerted in a direct line below the rung on which they are hooked.

For the purpose of preventing the ladder from slipping when the above described device is in use, there is provided a bracing tie consisting of rigid telescoping members 26 and 27 respectively which may be adjustably positioned with respect to each other by means of a collar 28 and a set screw 29. These members are each provided at their free ends with a hook numbered 30 and 31 respectively, one of these hooks being adapted to engage a rung of the ladder and the other of the hooks being adapted to engage a ring secured to the side of the structure against which the ladder is supported.

It will be seen that there has been described and shown a means for carrying out all of the objects of this invention in a practical, efficient and satisfactory manner, but it is to be distinctly understood that the same is by way of illustration and example only and that various changes in the construction and arrangement of parts may be made without departing from the spirit or scope of this invention as set forth in the appended claims.

What I claim is:—

1. A ladder bracket comprising a horizontally disposed supporting element provided with means intermediate its ends for supporting a scaffold, means adjacent each of its ends for arresting the shifting of the scaffold thereon, vertical means extending upwardly from its inner end for detachably suspending such end from a lower rung of the ladder and means to provide a looped outer end, a hanger element having means at one end for detachably connecting it to a rung of the ladder above the said lower rung, an extension element having oppositely inclined upper and lower stretches, means for connecting said upper stretch to the lower end of said hanger element, and means for connecting said lower stretch to

- the looped end of the supporting element whereby said looped end is suspended and the supporting element held in horizontal position.
2. A ladder bracket comprising a horizontally disposed supporting element provided with means intermediate its ends for supporting a scaffold, means adjacent each of its ends for arresting the shifting of the scaffold thereon, vertical means extending upwardly from its inner end for detachably suspending such end from a lower rung of the ladder and means to provide a looped outer end, a hanger element having means at one end for detachably connecting it to a rung of the ladder above the said lower rung, an extension element having a curved inner stretch and oppositely inclined upper and lower stretches, said upper stretch being bifurcated and having the lower end of said hanger element extended therein, said lower stretch extending into said looped end, means for securing the upper stretch to said hanger element, and means for securing said lower stretch to said looped end whereby said supporting element is held in horizontal position.
3. In a ladder bracket of that type including a horizontally disposed platform or scaffold supporting element adapted to have one end thereof coupled with an upper rung of the ladder and its other end directly connected with a lower rung of the ladder, said element comprising a head and a stem, said head formed of a central solid oblong part having each of its ends provided with an extension, elbows mounted on and projecting laterally from said extensions and upstanding hooks at the outer ends of the elbows for detachable direct connection with the lower rung of the ladder, and said stem formed of a pair of stretches, one being solid and merging at one end into one side of said part and at its other end into one end of said other stretch, the said other stretch being of looped form to provide an oblong vertically disposed opening, that stretch of looped form being for receiving a means for connecting the outer end of said element with the upper rung of the ladder and having the side walls of said opening formed with aligning apertures for the passage of a holdfast device to couple said means to the said stem.
4. In a ladder bracket of that type including a horizontally disposed platform or scaffold supporting element adapted to have one end thereof coupled with an upper rung of the ladder and its other end directly connected with a lower rung of the ladder, said element comprising a head and a stem, said head formed of a central solid oblong part having each of its ends provided with an extension, elbows mounted on and projecting laterally from said extensions and upstanding hooks at the outer ends of the elbows for detachable direct connection with the lower rung of the ladder, said stem formed of a pair of stretches, one being solid and merging at one end into one side of said part and at its other end into one end of said other stretch, the said other stretch being of looped form to provide an oblong vertically disposed opening, that stretch of looped form being for receiving a means for connecting the outer end of said element with the upper rung of the ladder and having the side walls of said opening formed with aligning apertures for the passage of a holdfast device to couple said means to the said stem, the said solid stretch being for supporting the platform or scaffold, and said looped stretch and central part being extended above said solid stretch to provide abutments at the ends of the ladder.
